CEILING TILE

Charles W. Allen, Jr., Des Plaines, Ill., assignor to The Celotex Corporation, Chicago, Ill., a corporation of Delaware

Filed Sept. 5, 1961, Ser. No. 66,611

Term of patent 14 years

(Cl. D18—2)

Fig. 1.

3

Fig. 2.

Fig. 3.

FIGURE 1 is a front face view of a ceiling tile showing my new design; and

FIGURE 2 is an edge view of said ceiling tile.

FIGURE 3 is an enlarged perspective view of the surface of FIGURE 1 enclosed within 3—3.

I claim:

The ornamental design for a ceiling tile, as shown.
